UNITED STATES PATENT OFFICE.

PAUL M. HOTCHKIN, OF CHICAGO, ILLINOIS.

BANK-SCREEN-LIGHTING DEVICE.

Application filed October 16, 1925. Serial No. 62,701.

The present invention relates to lighting fixtures, and is particularly concerned with fixtures of the elongated casing type used in banking institutions for the purpose of illuminating the desks in the cages.

The principal object of the invention is to provide an improved lighting fixture of the type described which is pleasing in appearance, is light, strong and durable in construction, is inexpensive to manufacture, and may be readily assembled in single or multiple unit lengths from a number of simple interfitting parts.

Another object is to provide such a fixture wherein the parts are shaped and brought together in ways which afford convenient access to all of those points where adjustments, repairs or replacements may at times be found necessary.

Still another object is to provide such a fixture which may be made up in either curved or straight form without requiring the employment of specially designed interior framework for the curved form.

Other objects and advantages will be evident to those skilled in the art upon a full comprehension of the construction of the fixture.

In order that the invention may be readily understood, one preferred structural embodiment of the same is illustrated in the accompanying drawings and is hereinafter described. It is to be understood however, that such particular embodiment is presented merely for the purpose of exemplification, and is not intended to in any way limit by its structural details the comprehensive scope of the invention as defined in the appended claims.

In the drawings:

Fig. 1 is a side view of a fixture constructed in accordance with the invention;

Fig. 2 is a top view of the fixture;

Fig. 3 is a bottom view of the same;

Fig. 4 is a vertical section taken on the line 4—4 of Fig. 2;

Fig. 5 is a vertical section taken on the line 5—5 of Fig. 2;

Fig. 6 is a vertical section taken on the line 6—6 of Fig. 2;

Fig. 7 is a perspective view of one of the members for retaining the ends of the wireways in the openings in the wiring boxes;

Fig. 8 is a perspective view of one of the members for sealing the unused openings in the wiring boxes;

Fig. 9 is a vertical section taken on the line 9—9 of Fig. 2;

Fig. 10 is a vertical section taken on the line 10—10 of Fig. 9;

Fig. 11 is a top view of one end of the fixture, with the cover removed, showing in horizontal section the portions of the wiring boxes which connect with the wireways;

Fig. 12 is a horizontal section through the end wiring box shown in Fig. 11, taken on the line 12—12 of Fig. 5;

Fig. 13 is an end view of an adjustable socket for inclusion in the fixture;

Fig. 14 is a top view of the socket;

Fig. 15 is a side view of the same, showing in vertical section the adjacent portions of the wiring box with which the socket is associated;

Fig. 16 is a vertical section through one of the direct-indirect reflectors in the fixture;

Fig. 17 is a vertical section taken on the line 17—17 of Fig. 16; and

Fig. 18 is a top view of a portion of the fixture when produced in a curved form, the portion of the top closure over the wiring box being removed to show the way in which the lamp socket is adjusted in order to position the center of the lamp properly with respect to the reflector.

The fixture illustrated in the drawings consists of an elongated casing 10 which is provided interiorly with end frame members 11 and intermediate frame members 12. The casing is divided by the members 12 into separate compartments 13, and electric lamps 14 are arranged in the compartments in sockets 15 provided adjacent the inner faces of the end members 11 and the opposite faces of the intermediate members 12.

The front and rear sides 16 of the casing are sheet metal panels which are embossed, as shown in Figs. 5 and 6, to form ornate upper and lower mouldings 17 on the outside of the casing. The upper mouldings terminate in inwardly extending flanges 18 which support the top closures of the compartments, and the lower mouldings 19 terminate in upwardly extending flanges 19 which support the bottom closures.

The several compartments 13 of the casing are capable of furnishing direct, indirect or both direct and indirect illumination to the desk or other working plane above which the fixture is mounted, the

character of the illumination depending upon the top and bottom closures used for the compartments and the arrangement therein of the reflectors with relation to the lamps. The compartment shown in the drawings at the right in Figs. 1 to 4 inclusive is equipped for direct illumination of the working plane below the fixture, and has, for its top closure, an imperforate sheet metal panel 20, and, for its bottom closure, a translucent glass panel 21, whereby the rays from the lamps in the compartment are cast downwardly through the bottom of the casing. The compartment shown at the left is equipped for indirect illumination, and has, for its top closure, two sheet metal rims 22 in which are supported the upper edges of two upwardly facing reflectors 23, and, for its bottom closure, a sheet metal panel 24, whereby the rays from the lamps are cast upwardly through the top of the casing. The compartment shown in the middle is equipped for both direct and indirect illumination, and has, for its top closure, sheet metal rims 25 in which are supported the upper edges of two upwardly facing reflectors 26 having translucent central portions 27, and, for its bottom closure, a translucent glass panel 28. It is to be understood that the particular combination of lighting effects given by the fixture is one which is presented merely for the purpose of exemplification, as quite obviously all or any number of the compartments may be made up in such a way as to furnish the same kind of illumination.

The panel 20 and the rims 22 and 25, which constitute the top closures for the compartments, are seated on the flanges 18 of the side panels, and are clamped in position by the overlapping margins of cover plates 29 which are screwed down upon the upper portions of the frame members 11 and 12. The ends of the rims 22 and 25 which are not secured by the plates 29 are clamped in position, as shown in Figs. 4 and 9, by plates 30 which are screwed to cross strips 31 positioned interiorly of the casing with their ends under the flanges 18 of the side panels 16.

Each of the end frame members 11 consists of a transversely disposed rectangular frame which has in the upper portion thereof an upwardly open wiring box 32, as shown in Figs. 5, 11 and 12. The outer face of the member 11 is closed in order to form an end cap for the casing, and such cap is ornamented marginally with both vertical and horizontal mouldings 33 and is provided inwardly of the mouldings with vertical side grooves 34 which receive the ends of the side panels 16. The sides 35 of the member hold the side panels in properly spaced relation, and the bottom 36 of the member supports one end of the adjacent

glass panel 21 or other bottom closure. The side panels 16 are held against withdrawal from the grooves 34 in the members 11 by means of bolts 37 which transfix lapped portions of the mouldings 33 and the panels.

The wiring box 32 in each of the end frame members 11 supports the associated lamp socket 15 from a generally rectangular plate 38 which is secured to the inner face of the box over an aperture 39 therein, and the wires from the socket extend through the aperture into the box. The plate 38 is held in position by screws 40 in the box which pass through horizontally elongated slots in the plate, the purpose of the elongation being to permit the plate to be adjusted horizontally in correcting alignment of the center of the lamp with respect to the associated reflector. If extreme adjustments are required, the screws 40 may be withdrawn from the apertures in which they are shown and inserted in other laterally offset apertures 41. The socket 15 is removably attached to the plate 38 by means of screws 42, and is positioned nearer one edge of the plate than the other, whereby, when it is desired to shift the position of the center of the lamp vertically relative to the reflector, the plate 38 need merely be reversed in position on the box 32.

The intermediate frame members 12 are somewhat similar to the end members 11 in that each consists of a transversely disposed rectangular frame which has in the upper portion thereof an upwardly open wiring box 43, as shown in Figs. 6 and 11. The sides 44 of the member hold the side panels 16 in properly spaced relation, and the bottom 45 of the member supports one end of the adjacent glass panel 21 or other bottom closure. The bottom 45, which is in the nature of a mullion, is provided with a medial rib 46, as shown in Fig. 4, and the adjacent edges of the panel 21 or other closure are positioned against such rib. The side panels 16 are held against the sides 44 of the member 12 by having the lower mouldings 17 of the panels hooked about corner pieces 47 on the member, and by having removable plates 48 hooked into the upper mouldings 17 and held against the member by screws 49. The member 12 is provided with T-shaped slots 50 for the reception of the screws 49, and the slots 50 are elongated longitudinally of the casing, as shown in Fig. 4, in order that the points of connection between the side panels 16 and the member may be shifted if desirable.

The wiring box 43 in each of the intermediate frame members 12 supports two of the lamp sockets 15 from two generally rectangular plates 51 which are secured to the opposite faces of the box over apertures 52 therein, and the wires for the sockets extend through the apertures into the box. The

socket supporting plates 51 are adjustably secured to the box 43 in substantially the same manner as the plate 38 is secured to the box 32 of one of the end frame members 11. The wires for supplying the several lamps 14 with electric current are carried from one wiring box to another through sheet metal wireways 53 of shallow channel form. Each of the wireways 53 is disposed with its open side against one of the side panels 16, as shown in Figs. 5 to 12 inclusive, and with its ends 54 in alignment with correspondingly shaped openings 55 in the faces of the wiring boxes 32 and 43. The openings 55 are in direct communication with the interiors of the wiring boxes. The wireways 53 are held against the side panels 16 and in alignment with the openings 55 in the frame members by means of retaining plates 56 which slide into guide grooves 57 located in the faces of the frame members at points above and below the wireways. The plates 56, when properly positioned, bear with the intermediate portions 58 of the same against the intermediate portions of the ends of the wireways. The plates 56 are provided with deformable tongues 59, and, when the plates 56 have been positioned against the wireways, the tongues 59 may be bent abruptly into the wiring boxes, as shown in Figs. 11 and 12, whereby to prevent accidental displacement of such plates. It is, of course, only necessary to use one wireway between any two frame members, but, since the end members 11 are preferably identical at both ends of the casing, such members must necessarily be provided with wireway openings 57 on both sides of the inner faces of the same if the wireways are to extend throughout the casing along but one side thereof. One of the openings 55 in each of the end members 11 is therefore not used, and such opening may be closed off from the adjoining compartment 13 by means of a sealing plate 60 which is inserted in grooves 57 and locked in position in substantially the same manner as the retaining plates 56. The sealing plates 60 differ essentially from the retaining plates, however, in that they are provided with abrupt flanges 61 which extend across and completely close the associated opening 55.

Lighting fixtures such as those herein described are sometimes required in rather long sizes, and the longer fixtures cannot be shipped conveniently in assembled form. In order to provide a knock-down construction for convenience in both manufacture and shipping, the side panels 16 may be in the form of two medially abutting panels 62 and 63, as shown in Figs. 9 and 10, and such panels may be rigidly spliced together by means of strips 64 which fit into the recesses resulting from the formation of the upper and lower mouldings 17. The strips are

provided at intervals with longitudinal slots 65, and bolts 66 extend through the mouldings 17 and strips 64 at those points to clamp the same rigidly together. The joint may be hidden as well as additionally reinforced by means of two exterior side clamping strips 67 which are secured firmly against the sides of the casing by the middle set of bolts 66. This arrangement provides an extremely simple, yet strong and easily assembled joint, and permits splicing to be effected with a high degree of permanency.

It is sometimes necessary that the fixture be formed up in curved as distinguished from straight form in order to meet special requirements. The fixture of the invention is particularly well adapted for this, as it is only necessary to impart the desired curvature to the side panels 16, and to cut the removable top and bottom closures to the required shape. No change is necessary in the end or intermediate frame members 11 and 12, as they will not interfere with the curvature of the side panels, but it is desirable to substitute, in place of each of the sockets 15 and socket supporting plates 38 and 51, an interchangeable swivel socket and plate such as shown in Figs. 13, 14, 15, and 18, so that the center of the lamp 15 may be swung into position in alignment with the center of the associated reflector. The swivel socket 67 referred to is pivoted at 68 to the supporting plate 69, and is provided with a ball-shaped rear portion 70 which turns about the axis 68 within a snugly fitting aperture 71 in the plate 69. The aperture 71 of course covers a larger aperture in the face of the associated wiring box. The plate 69, like the plates 38 and 51, may be reversed in position upon the wiring box in order to vary in a vertical plane the position of the center of the lamp, and is also adjustable laterally on the box whereby to permit it to be shifted into such an offset position for instance as that shown in Fig. 18, as a result of which shifting the lamp 15 is brought into perfect alignment with the associated reflector.

The usual wire carrying conduit preferably enters the fixture through an aperture 72 in one of the end wiring boxes 11, as shown in Fig. 12, and the wires are distributed from that point to the several wiring boxes through the connecting wireways. The electrical circuits are preferably controlled by means of a pull-chain switch 73, or other suitable means, located in one of the wiring boxes.

I claim:—

1. A fixture of the class described, comprising an elongated casing, wiring boxes in the casing, a wireway between the boxes, and retaining members slidably positioned in grooves in the boxes and bearing transversely against the wireway near the ends

thereof for holding the same in alignment with openings in the boxes.

2. A fixture of the class described, comprising an elongated casing, wiring boxes 5 in the casing, a wireway between the boxes, retaining members slidably positioned in grooves in the boxes and bearing transversely against the wireway near the ends thereof for holding the same in alignment with 10 openings in the boxes, and tongues on the retaining members deformable to hold the members against displacement after being positioned in the grooves against the wireway.

15 3. A fixture of the class described, comprising an elongated casing, two interchangeable end wiring boxes in the casing having wireway openings at both sides of the casing, one or more intermediate wiring 20 boxes in the casing having wireway openings at but one side of the casing, wireways extending between all of the wiring boxes, means for holding the wireways in alignment with the wireway openings in the 25 boxes at one side of the casing, and means for sealing the unused openings in the end boxes at the other side of the casing.

4. A fixture of the class described, comprising an elongated casing, two interchangeable end wiring boxes in the casing having wireway openings and slide positioning grooves at both sides of the casing, one or more intermediate wiring boxes in the casing having wireway openings and 35 slide positioning grooves at but one side of the casing, wireways extending between all of the wiring boxes, removable slides engageable in the grooves for holding the wireways in alignment with the wireway 40 openings in the boxes at one side of the casing, and other slides engageable in the grooves for sealing the unused openings in the end boxes at the other side of the casing.

45 5. A fixture of the class described, comprising an elongated casing, wiring boxes so arranged in the casing as to form therebetween lamp chambers, means for closing the tops of the chambers, and means overlapping the chamber closing means for closing 50 the tops of the boxes.

6. A fixture of the class described, comprising an elongated casing having two sheet metal side panels, transversely disposed frame members against the sides of which the side panels are positioned, means on one of the frame members for interlocking with the lower portions of the side panels, anchor members for interlocking with the upper portions of the side panels, and screw connections between the anchor members and the frame members operable to hold the side panels of the casing in fixed position relative to the frame member.

7. A fixture of the class described, comprising an elongated casing having two sheet

metal side panels, transversely disposed frame members against the sides of which the side panels are positioned, means on one of the frame members for interlocking with the lower portions of the side panels, anchor members for interlocking with the upper portions of the side panels, and screw connections between the anchor members and the frame member operable to hold the side panels of the casing in fixed position relative to the frame member, said anchor members being shiftable longitudinally of the side panels, and said screw connections being shiftable longitudinally of the frame member.

8. A fixture of the class described, comprising an elongated casing, members so arranged in the casing as to form compartments therebetween, sockets pivotally associated with the members for supporting lamps in the compartments, and means for permitting the sockets to be pivotally associated with the members in different positions laterally of the members.

9. A fixture of the class described, comprising an elongated casing, members so arranged in the casing as to form compartments therebetween, plates associated with the members at the ends of the compartments, screws passing through top and bottom apertures in the plates for detachably securing the plates to the members, and lamp sockets carried by the plates at unequal distances from the top and bottom apertures in order to effect a variation in the vertical positions of the sockets upon reversal of the plates relative to the members.

10. A fixture of the class described, comprising an elongated casing, members so arranged in the casing as to form compartments therebetween, plates associated with the members at the ends of the compartments, screws passing through horizontally elongated slots in the plates for detachably securing the plates to the members in different positions laterally of the members, and lamp sockets carried by the plates.

11. A fixture of the class described, comprising an elongated casing having two sheet metal side panels which are each transversely divided, and means for splicing the sections of each side panel together, consisting of two longitudinally extending strips spanning the sections of the panel and positioned against the inside of the same adjacent the top and bottom margins, a transversely extending strip overlying the division between the sections and positioned against the outside of the panel, and means for clamping all of the strips fixedly against the sections.

12. A fixture of the class described, comprising an elongated casing having two sheet metal side panels which are longitudinally embossed to provide exterior mouldings and are each transversely divided, and means

for splicing the sections of each side panel together, consisting of two longitudinally extending strips removably set into the grooves formed on the inside of the sections by the mouldings, and means for clamping the strips fixedly against the sections.

13. A fixture of the class described, comprising an elongated casing of curved form having two sheet metal side panels, transversely disposed frame members against the sides of which the curved side panels are positioned, means for attaching the side panels to the frame members, sockets associated with the frame members for holding lamps in the casing between the frame members, reflectors carried by the casing between the frame members, and connections between the sockets and the frame members for permitting the sockets to be shifted into positions wherein the lamps held thereby will be in vertical alignment with the reflectors irrespective of the curvature of the casing.

14. A lighting fixture of the class de-

scribed, comprising an elongated casing, a lamp in the casing adapted to cast light rays through two opposite parallel faces of the same, and a reflector in the casing adjacent the lamp, said reflector having a flat translucent central zone parallel to one face of the casing through which certain of the light rays from the lamp will pass and a curved opaque surrounding zone symmetrical with respect to the opposite face from which other of the light rays will be reflected.

15. A fixture of the class described, comprising an elongated casing, wiring boxes so arranged in the casing as to form therebetween lamp chambers, elongated panels extending between the boxes for closing the tops of the chambers, and small plates overlapping the ends of the panels for closing the tops of the boxes and holding the panels in position.

In testimony whereof I have hereunto signed my name.

PAUL M. HOTCHKIN.
